TOBACCO PIPE

Samuel J. Harris, Dayton, Ohio

Application September 2, 1932, Serial No. 631,447

4 Claims. (Cl. 131—12)

This invention relates to pipes in which to smoke tobacco, and more particularly to pipes adapted to deliver cool, pure smoke to the mouths of smokers.

While efforts have been made to produce pipes adapted to deliver cool, pure smoke, I believe my improvements are more effective than any heretofore produced. Furthermore, I have found a new method whereby to obtain this result, namely, the introduction of air into the smoke, which air becomes thoroughly mixed with the smoke before it reaches the smoker's mouth.

Fig. 1 is a longitudinal sectional elevation of my pipe, and

Fig. 2 is a sectional plan of the tobacco bowl and cooling chamber, taken on line 2—2 of Fig. 1.

The pipe comprises a tobacco bowl 10, a cooling chamber 11, a passage 12, connecting the bowl and cooling chamber, a stem 13, and a passage 14 that taps the cooling chamber at its upper part and carries smoke through the stem to the mouth of the smoker. The bottom of the cooling chamber consists of a removable cap 15, which screws on a nipple 16 that is secured in the chamber. The pipe may be made of any suitable material, such as wood or meerschaum, and preferably the cap 15 and nipple 16 are made of metal. At 17 a small hole or vent is bored through the rear wall of the cooling chamber 11. The passage 12 may be radial to the chamber 11, as in Fig. 1, or tangential, as in Fig. 2.

One function of the chamber 11 is to cool the smoke. This results from the fact that only a small portion of the wall area of the cooling chamber is heated by the burning tobacco in the bowl, all of the remainder of the wall area being exposed to the cooling influence of the atmosphere. The smoke passes through the chamber slowly and lazily, giving it time to be cooled by contact with the comparatively cool wall of the chamber. The smoke naturally rolls through the chamber in the characteristic way in which smoke rolls from a chimney. Where the passage 12 is tangential, as in Fig. 2, a circular or helical movement is imparted to the smoke in the chamber. This circular movement produces centrifugal force which throws the smoke against the chamber wall and cools it more effectually. In order to reduce the area of heated chamber wall, a slot 18 may be cut between the bowl and chamber, as in Fig. 1, leav-

ing only enough material around the passage 12 to properly unite the parts.

There is an advantage in having the smoke enter the chamber 11 at its lower part and leave at its upper part. When the smoker is drawing on the stem the smoke is made to move upward in the chamber. Between drafts the smoke ceases to rise, and at least part of it begins to gravitate. The smoke is the gaseous product of the burning tobacco, the visible portion of the smoke being small particles of carbon. This solid matter being heavier than the gas it falls toward the bottom of the chamber when there is insufficient upward draft to sustain or raise it. Thus the intermittent drafts at the stem result in alternate up and down movement of the smoke in the chamber. During these up and down movements some of the solid particles in the smoke, especially the larger ones, gravitate to the bottom of the chamber, whence they can be removed from time to time, together with any other foreign matter that may have accumulated there by removing the cap 15. In this way a considerable degree of purification of the smoke is effected.

Further purification of the smoke is effected by the jet of cool air that enters the chamber 11 through the vent 17. This jet of air passing transversely of the rising column of smoke condenses the nicotine in the smoke, which becomes precipitated to the bottom of the chamber and is removed along with other matter when the chamber is cleaned. Where the smoke is caused by the tangential passage 12 to move in a circular path the jet of air is still more effective as a purifying agent. The nicotine being the most pernicious element in tobacco it is evidently a useful service to remove more or less of it from the smoke. The vent 17 is also very effective in cooling the smoke, thereby delivering cool smoke to the stem.

The vent 17 is enough smaller than the passage 12 so that it does not materially reduce the draft through the bowl. Moreover, the size of the vent may be varied according to the amount it is desired to dilute or cool the smoke.

The chamber 11 serves as a receptacle for small particles of tobacco or ash that may pass through the passage 12. It also receives saliva or other fluid that may flow from the stem, all of which accumulate in the lower part of the chamber to be removed from time to time through the large opening afforded by unscrewing the cap 15.

While I have illustrated and described what

at this time I regard as the best mode of putting my invention into practice, it is not to be understood that the invention is limited in its scope to the particular structure shown, as various modifications are possible without departure from the spirit of the invention.

Having fully described my invention I claim:

1. In a tobacco pipe, a tobacco bowl, a tubular stem, and a chamber through which smoke passes in moving from the bowl to the stem, the connection from the bowl to the chamber being lower than the connection from the chamber to the stem, the side wall of the chamber being concentric to its vertical axis, free from projections, and having an opening for a vent at a height intermediate said connections from the bowl to the chamber and the chamber to the stem, said chamber having a capacity approximately equal to the capacity of the bowl, thereby causing the smoke to pass through it slowly and lazily.

2. In a tobacco pipe, a tobacco bowl, a tubular stem and a cylindrical chamber through which smoke passes in moving from the bowl to the stem, the connecting passage from the bowl to the chamber being lower than the passage from the chamber to the stem, and substantially tangential, thereby causing the smoke

to move in a substantially helical path in the chamber, and a vent through which air enters the chamber to mix with the smoke.

3. In a tobacco pipe, a tobacco bowl, a tubular stem and a cylindrical chamber through which smoke passes in moving from the bowl to the stem, a passage connecting the bowl and chamber, said passage being substantially tangential to an imaginary circle of which the vertical axis of the chamber is the axis, whereby the smoke in the chamber is made to move in a substantially circular or helical path, and a vent through which air enters the chamber to mix with the smoke.

4. In a tobacco pipe, a tobacco bowl, a tubular stem, and a chamber through which smoke passes in moving from the bowl to the stem, said chamber and bowl being parallel and approximately the same size, integral and having the appearance of being integral, but isolated by a narrow, inconspicuous saw-cut, which leaves them connected by a neck containing a passage through which smoke passes from one to the other, said neck being comparatively small and near the bottom of the bowl, so as to conduct but little heat from the bowl to the chamber.
